UNITED STATES PATENT OFFICE.

ELMER C. DUNN, OF KEOUK, IOWA.

CLOTHES STICK.

Application filed January 13, 1928. Serial No. 246,636.

This invention relates to new and useful improvements in clothes sticks.

One object of the invention is to provide a clothes stick which is of such construction that the clothes will not slip therefrom, when the clothes are being lifted from the water, by means of the stick.

Another object is to provide a terminal for a clothes stick which may be readily attached 10 to any ordinary stick, and whereby the lifting of the clothes is greatly facilitated.

Another object is to provide a terminal or tip for a clothes stick which will not wear out readily, and which will not tear or 15 otherwise injure the clothes.

Other objects and advantages will be apparent from the following description when taken in connection with the accompanying drawing.

20 In the drawing:

Figure 1 is a perspective view of an end of a clothes stick showing the tip or shoe attached thereto.

Figure 2 is a perspective view showing 25 the parts separated from each other.

Referring particularly to the accompanying drawing, 10 represents a portion of a clothes stick, which as illustrated in the drawing is angular in cross section, although 30 this may be varied according to the desires of the manufacturer or purchaser. The stick is preferably formed from wood, which renders the same comparatively light in weight, and permits easier manipulation.

35 On the end of the stick is secured a metal tip, represented as a whole by the numeral 11, such tip being composed of two halves 12 and 13, each having an angular channeled portion 14, which snugly embraces the end of 40 the stick, the flanges of such portions being disposed in overlapping relation to each other, and nails, or other suitable fastening devices 15, driven through the said portions 14, into the stick end. Beyond the end of 45 the stick the members 12 and 13, which are preferably formed from some light metal, are curved downwardly and outwardly away from one edge of the stick, to form a foot 16, and on the upper concave portion of such 50 foot there are formed the transverse corrugations 17. The foot is, in effect, a hook, which facilitates the lifting of the clothes from the water, and by reason of the corrugations, the clothes are held from slipping 55 from the foot.

It will be noted that the flanges of the

members 12 and 13 are of approximately the same width so that when properly engaged together and secured to the end of the stick, the foot portions will be held in 60 rigid position, without any tendency to flex toward and away from each other.

When the stick is plunged into the water containing clothes, and the operator manipulates the stick to lift a portion of such 65 clothes, the corrugations of the foot of the stick will serve to prevent such clothes slipping, so that the clothes may be successfully lifted from the water.

The foot has a smooth exterior, and round- 70 ed edges so that there will be no tearing or otherwise injuring the clothes.

While I have shown the foot as adapted for attachment to a stick end having an angular cross section, I wish it understood 75 that the foot may be made to apply to a stick of circular cross section, or any other cross section desired. I do not wish to be limited to the degree of curve of the foot, as such foot may be more or less sharply 80 curved, or may be of greater or less length.

What is claimed is:

1. A terminal for a clothes stick comprising a hollow casing longitudinally arcuate and having one end open to receive the end 85 of the clothes stick, said casing having transverse corrugations in its concave face.

2. A terminal for a clothes stick comprising a hollow two part casing longitudinally arcuate and having one end open to receive an end of the clothes stick, each of the parts of the casing having transverse corrugations in its concave face which nest with the corrugations of the other part and having its convex face smooth. 95

3. A terminal for an end of a clothes stick comprising a two part longitudinally arcuate casing having one end open for the reception of an end of the stick, the convex face of each of the casing parts being 100 smooth while each concave face is formed with transverse corrugations, the edge portions of the casing parts being disposed in overlapping relation to each other when applied to the stick end and provided with 105 fastening receiving openings in the stick end receiving opening, the corrugations of one casing part nesting with the corrugations of the other casing part.

In testimony whereof, I affix my signature.

ELMER C. DUNN.
